Attorneys.

UNITED STATES PATENT OFFICE.

JOHN F. LIETZ, OF BUFFALO, NEW YORK.

ROOFING CONSTRUCTION.

Application filed June 16, 1927. Serial No. 199,260.

This invention relates more particularly to flexible composition shingles of substantially diamond shape having locking parts or members at their lower corners.

- 5 One of the objects of the invention is the improvement of such shingles, with a view of simplifying their construction, reducing their cost of manufacture and producing a smooth roof without bulges.
- 10 Another object is to so construct the shingles that they can be readily adjusted both vertically and laterally in laying them, in order to compensate for inequalities or misalignment and improve the appearance of
- 15 the roof.

In the accompanying drawing, Figure 1 is a fragmentary top plan view of a roof embodying my invention. Figure 2 is a similar view on an enlarged scale, showing 20 one of the shingles folded back to expose its locking staples. Figure 3 is an enlarged horizontal section on line 3—3 Figure 2. Figure 4 is a transverse section on line 4—4 Figure 1. Figure 5 is a perspective view of 25 one of the locking staples. Figure 6 is a view similar to Figure 3 showing a modified form of the staple.

Similar characters of reference indicate corresponding parts throughout their views. 30 10 indicates the usual roof boards or sheathing and 11 the starting strip of roofing material laid along the lower margin of the roof.

The shingles 12 are preferably constructed 35 of composition roofing, such as felt saturated with asphalt and faced with crushed slate or other appropriate material. They are laid diagonally in the customary overlying courses, with the side corners of shingles in the same row abutting or adjacent to each other as shown. Each shingle is provided 40 at its lower end or corner with a tongue 13 preferably integral with the shingle-body and cut simultaneously therewith. In 45 the preferred construction shown, the tongue is formed by cutting a pair of opposing notches 14 in the edges of the lower shingle-corner. This manner of cutting brings the tongue within the dimensional lines of the 50 shingle and reduces waste of material to a minimum. Each side corner of the shingle is cut with a notch 15, the two registering notches of a pair of adjacent shingles together forming a recess 16 adapted to receive 55 the tongue 13 of a similar shingle in the overlying course, allowing the tongue to lie

flush with the face of the underlying shingles and producing a smooth roof over its entire surface.

Any appropriate means may be employed 60 to lock the shingle tongue in the recess 16. The preferred devices consist of a pair of L-shaped staples 17, driven through the opposing side corners of the pair of underlying shingles and under which the tongue 65 is inserted, as best shown in Figures 2 and 3. The heads 18 of the staples face each other, preferably without meeting, but are of sufficient extent to overlap the margins of the locking tongue and reliably hold it in 70 place. These staples thus serve the double purpose of locking the tongue of one shingle and fastening the opposing side corners of the pair of underlying shingles. In applying and locking a shingle, its tongue may either be left unfolded, as shown in Figure 75 2, and inserted under the heads of the staples in that position and the shingle body then folded over the tongue to the final position shown in Figure 1; or the tongue may be turned under the shingle body and the shingle then moved upward to hook the tongue under its companion staples. In either case, the staples are fully concealed 80 and protected from the weather by the shingles. As the tongues of overlying shingles enter the notches of underlying shingles, the tongues can be easily inserted under the retaining members 18 or 19 without buckling, and being flush with adjoining 85 shingles, the tongues do not produce bulges in the roof, leaving it flat, smooth and slightly.

The shingle tongues and their receiving recesses 16 are long enough to permit the shingles to be shifted vertically to a sufficient extent to accurately align the shingles in the same horizontal row, and yet retain the tongue with the necessary security to withstand the force of windstorms. As 90 shown in Figures 2 and 3, the recesses are somewhat wider than the tongues to permit a certain amount of side play of the tongues. This provision enables the roofer to adjust the shingles laterally more or less at or near the end of the roof, or a valley, to bring the side corners of all the shingles in the same 95 row against one another and produce a slightly, uniformly laid roof.

The several advantages above described 100 are obtained by an exceedingly simple and inexpensive construction of the shingles and

their locking devices and without sacrificing the strength and security of the lock.

The L-shaped staples are suitable at the ends of a roof or valley, as well as at other 5 places and they are therefore preferred, but any other appropriate means may be substituted for them. For example, ordinary U-shaped staples 19 wide enough to bridge the locking tongue and penetrate the adjacent 10 underlying shingles may be used, if desired, as shown in Figure 6.

I claim as my invention:—

1. In a roofing construction, a pair of flexible diagonally-laid shingles notched in 15 their opposing side edges, forming a recess, a third shingle overlying said pair and provided at its lower end with a locking tongue lying in said recess, the latter being wider than said tongue, permitting lateral adjustment of the last-named shingle relative to 20 said first-named pair, and means for retaining the tongue in said recess.

2. In a roofing construction, a pair of flexible diamond-shaped diagonally-laid shingles provided in their opposing side corners with 25 notches, together forming a downwardly-opening recess, a third shingle overlying said pair and provided at its lower end with a locking tongue lying flush in said recess, and means for retaining the tongue in said recess. 30

3. In a roofing construction, a pair of flexible diamond-shaped diagonally-laid shingles provided in their opposing side corners with registering notches, forming a downwardly-opening recess, L-shaped staples whose stems penetrate the side portions of 35 said pair respectively, while their heads extend over said notches, and a third shingle provided at its lower corner with a turned-under locking tongue lying flush in said recess and engaging under the heads of said staples. 40

JOHN F. LIETZ.
